ATTORNEY

UNITED STATES PATENT OFFICE.

JAMES M. GREEN, OF CHICAGO, ILLINOIS, ASSIGNOR, BY DIRECT AND MESNE ASSIGNMENTS, OF ONE-FOURTH TO FREDERIC A. CURTIS, OF CHICAGO, ILLINOIS, AND ONE-FOURTH TO JOSEPH E. McCUALEY, OF SYLVANIA, OHIO; THE NORTHERN TRUST COMPANY, ADMINISTRATOR OF SAID JAMES M. GREEN, DECEASED, ASSIGNS, BY MESNE ASSIGNMENTS, OF ONE-HALF TO BRILLIANT LIGHT COMPANY, OF CHICAGO, ILLINOIS, A CORPORATION OF ILLINOIS.

BURNER.

954,389.

Specification of Letters Patent.

Patented Apr. 5, 1910.

Application filed June 4, 1909. Serial No. 500,107.

To all whom it may concern:

Be it known that I, JAMES M. GREEN, a citizen of the United States, and a resident of Chicago, in the county of Cook and State 5 of Illinois, have invented certain new and useful Improvements in Burners, of which the following, when taken in connection with the drawing accompanying and forming a part hereof, is a full and complete 10 description, sufficient to enable those skilled in the art to which it pertains to understand, make, and use the same.

This invention relates to burners for the combustion of kerosene, provided with 15 domes; and the principal objects of the invention are to obtain a burner which will produce, when in operation in a lamp, lantern, and the like, a large flame of proper shape and one which will give corresponding 20 large candle power, while at the same time but little attention or care is required to trim and light the wick of the burner.

Another and important object of the invention is to obtain a device which will retain 25 its shape during its handling and use.

A further object of the invention is to obtain a device which is economical in construction, uniform in production and a device whereof the several parts are attached 30 together in the same relative position in the manufacture of large quantities.

In the drawing referred to Figure 1 is a side elevation of a device embodying the invention, with the chimney thereof removed, and showing the principal part of its interior construction by broken lines. Fig. 2 is a vertical sectional view of the dome and deflector of the device, contained 35 in the dome, said parts forming the principal element of a device embodying the invention, on line 2—2 of Fig. 6, viewed in the direction indicated by the arrows. Fig. 3 is a vertical sectional view of the deflector of the device. Fig. 4 is an end elevation of 40 the deflector. Fig. 5 is a vertical section of the deflector, viewed at right angles to the section illustrated in Fig. 3. Fig. 6 is a horizontal section of the dome of the device, showing the deflector in top plan view; and 45 Fig. 7 is a plan view of the blank from which, by using duplicates, the deflector of the device is obtained.

A reference letter applied to designate a given part is used to indicate such part throughout the several figures of the drawing wherever the same appears.

A is the base of the burner, and B the dome. Base A is provided with foraminations C in the usual way.

D is the wick tube and d the wick raiser.

Dome B is hinged to base A, by hinge b, and is held in place by spring b', such being the usual construction.

E is a deflector within the dome B and attached thereto. Deflector E is arranged to 65 act in combination with dome B to direct the air which supports combustion onto the flame of the burner when the device is in use. Deflector E is made of two pieces (F) of sheet metal cut to shape, substantially as 70 illustrated in Fig. 7, and bent or formed on broken lines f, f'. The two pieces F are joined together as is hereinafter described. Sheet metal pieces F are respectively provided with lugs or projections G and H, and 75 with the aperture g. By bending the piece F on line f, the part I is made to form one side of the deflector E, when such piece F is joined to an additional piece F bent in the same manner, and the part J thereof is made 80 to form one end of said deflector. The two pieces F which are necessary to make a deflector are joined together by inserting the projection or lug G on each piece in the aperture g of the other piece, and then bending 85 the respective lugs on line g'. Either prior or subsequent to the joining of two of the pieces F together, as last above described, the metal included within broken lines f' is stamped or formed out into shape to obtain 90 recess K, one of said recesses in the part J of each of said pieces. These recesses, it will be observed, respectively progressively enlarge from the bottom thereof to the top edge of the deflector where a comparatively 95 large recess is obtained which comes nearly to but not in contact with the inner wall of the dome B which is adjacent thereof (as illustrated at k), when the deflector is joined to the dome in the manner and position 100 about to be described.

L, L, are apertures in the wall of dome B.

The length of the deflector E is determined by the distance between the broken

line *f* and the aperture *g*, Fig. 7, of piece F, and the portion of the part I of said piece F which is between the aperture *g* and the end *h* is of suitable length so that the ends *h*, 5 (of the two pieces F forming the deflector), are in contact with the inner face of dome B when projections H are in aperture L and said deflector and dome are thereby joined together with the deflector properly positioned 10 relative to the wick tube D and to said dome.

Piece F is made of sheet brass, steel or other suitable material. When sheet steel is used I prefer to electro-plate it with brass 15 or to cover it with tin as in the ordinary way of making what is known in commerce as sheet tin.

The dome B is made of thin metal, usually brass, in the ordinary way and the deflector 20 E, made as above set forth, is readily joined thereto by springing the wall of said dome so as to permit projections H to enter aperture L. When these projections are thus inserted they may be bent to insure the said 25 projections from coming out therefrom, but in practice I have not found it necessary to make said bend, (on line *g''*).

The deflector E constructed as above described and placed in position in dome B as 30 set forth, operates substantially as follows:—The recesses K, K, protect the base of the flame produced in the use of the device from sudden fluctuations which would otherwise occur in the flame, particularly if 35 the ends of the deflector be forced out in substantially broken line *f'*, Fig. 7; and said recesses apparently produce the effect of causing or permitting the flame at the ends thereof to widen out, above the dome B 40 while at the same time sufficient air to support the combustion of the enlarged flame is provided in proper manner and quantity so that no smoke is made by the enlargement and change of shape of said flame.

45 I find that a deflector made as described

and joined to the dome as described is rigidly held in place and that when a large number of burners are made having in each thereof a dome and a deflector uniformity of construction and result are readily obtained 50 and that the device is particularly valuable in this regard and in the fact that a steady flame of large size is produced by the use of the device.

Having thus described my invention what 55 I claim as new and desire to secure by Letters Patent is:—

1. The combination of a dome and a deflector, said dome provided with apertures in the walls thereof, and said deflector consisting of duplicate pieces joined together and to the dome, said duplicate pieces respectively consisting of a sheet of metal blank provided with an aperture and with projections, with one of the projections of 60 one piece in the aperture of the other piece and the remaining projections of said pieces in the apertures in the dome.

2. The combination of a dome and a deflector, said dome provided with apertures in 70 the walls thereof, and said deflector consisting of duplicate pieces joined together and to the dome, said duplicate pieces respectively consisting of a sheet metal blank provided with an aperture and with projections, 75 with one of the projections of one piece in the aperture of the other piece and the remaining projections of said pieces in the apertures in the dome, said pieces respectively provided with an outwardly flared 80 portion positioned to form recesses in the ends of the deflector, and said deflector positioned relative to the dome with the end walls of the recesses in the ends of the deflector near to the inner wall of the dome. 85

JAMES M. GREEN.

In the presence of—

F. A. CURTIS,
C. A. ADAMS.
